UNITED STATES PATENT OFFICE.

ALVIS JACKSON HATHCOX, OF DURANT, OKLAHOMA.

DOOR-CLOSER.

1,294,903.

Specification of Letters Patent. Patented Feb. 18, 1919.

Application filed May 27, 1918. Serial No. 236,835.

To all whom it may concern:

Be it known that I, ALVIS J. HATHCOX, a citizen of the United States, residing at Durant, in the county of Bryan and State 5 of Oklahoma, have invented certain new and useful Improvements in Door-Closers; and I do declare the following to be a full, clear, and exact description of the invention, such as will enable others skilled in the art to 10 which it appertains to make and use the same.

This invention relates to door closers, and it relates more particularly to an improved double acting device for holding a door or 15 the like in closed or open position.

One of the objects of this invention is to provide a device of this character which may be quickly, easily and conveniently attached to any door and door-casing; but 20 which is especially applicable for screen doors, window shutters and the like;

Another object is to provide a device of this character which is very simple of construction and comparatively inexpensive;

25 Another object is to provide a device of this character which is strong, durable, effective and thoroughly practical.

Other objects and advantages may become apparent to persons who read the following details of description in connection 30 with the accompanying drawings, in which:

Figure 1 is an elevation disclosing a door frame, screen door and my improved double acting device attached thereto;

35 Fig. 2 is a top plan view of the device, the half-open position being shown in dotted lines;

Fig. 3 is a view similar to Fig. 2 except that it shows the device in its position for 40 holding the door wide open;

Fig. 4 is a sectional detail view, the section being taken along line 4-4 of Fig. 2;

Fig. 5 is a sectional detail view, the section being taken along the line 5-5 of 45 Fig. 2;

Fig. 6 is a sectional detail view, the section being taken along line 6-6 of Fig. 2.

Referring to these drawings in detail, in which similar reference characters correspond with similar parts throughout the several views, the door casing 7 and screen door 8, being of ordinary construction, are not described in detail. The device which constitutes the present invention is disclosed 55 at the top part of Fig. 1, being secured to

the casing 7 by means of screws 9 which extend through apertures of a flange 10, said flange comprising a right-angle extension of a sheet metal plate 11 which is formed with an aperture 12 and a slot 11', the latter 60 extending from a point adjacent to the flange or attaching element 10 to a point adjacent to the opposite end of the plate. A lever 13 is pivotally connected to the plate 11 by means of a rivet or pivot 14 which extends through the aperture 12 and through a corresponding aperture in said lever 13. The lever 13 is pivotally connected to a link 15 by means of a rivet 16, and a washer 17 is disposed between the link 15 and lever 65 13. One of the links 15 is apertured to receive an element 18, one end of this element constituting a stud which extends through the slot 11' and travels therealong, the other end of the element 18 constituting a stud 70 which connects one end of a spring 19 with the link 15, the other end of the spring 19 being connected with the lever 13 through the medium of a wire loop or eye 20 which extends through one of several apertures 75 21 of the lever and has its ends extending in opposite directions and turning laterally of the edges of the lever, as clearly illustrated in Fig. 5. It may be seen that the sides of the slot 11' constitute a track or 80 guide for the element 18.

An apertured member 22 has a screw 23 extending through one of its apertures and secured to the upper part of the door, and the other aperture or loop 24 of the 90 member 22 receives the free end of the lever 13 and allows the latter to slide therethrough.

The members 11, 13, 15 and 17 are each 95 preferably formed by stamping from sheet metal, thereby reducing the cost of manufacture to the minimum, the other elements also being formed of comparatively inexpensive material such as wire and the like.

From the foregoing description, it will be 100 seen that when the device is in the dotted line position shown in Fig. 2, the action of the spring is held in alinement with the slot 11', so that the door is held in its half-open position. However, if the door is swung 105 toward the left, the spring 19 coöperates with the elements 11 and 15 for holding the lever 13 in its door-closing position; whereas, if the door is moved rightward from the dotted line position, the spring 19 coöper- 110

ates with said elements 11 and 15 for moving lever 13 into its door-opening position. It will be seen, therefore, that the device is equally effective for holding the door closed 5 or holding it wide open.

Although I have described this embodiment of my invention very specifically, it is not intended to limit this invention to these exact details of construction and arrangement of parts, but I am entitled to make changes within the scope of the inventive idea disclosed in the foregoing description and following claims.

What I claim as my invention is:

- 15 1. The combination of a support provided with a track, a lever pivotally connected to said support, a member pivotally connected to said lever and provided with an element that travels along said track and is guided thereby, and a spring having one end engaged with said lever and having its other end connected with said member and being coöperative with the latter and with said support to hold said lever in different positions relative to said support.
- 20 2. The combination of a support provided with a track, a lever pivotally connected to said support, a member pivotally connected to said lever and provided with an element that travels along said track and is guided thereby, and a retractile spring having one end connected with said lever and having its other end connected with said member between the points where the latter connect 30 with said track and said lever, whereby the said spring is coöperative with said support and said member so as to hold said lever in different positions relative to said support.
- 35 3. The combination of a sheet metal plate formed with an apertured attaching flange at one end and with a track extending from a point adjacent to the flange to a point 40

adjacent to the opposite end, a lever pivotally connected to said opposite end, a 45 member provided with an element slidably engaged with said track, said member being pivotally connected to said lever, and means associated with said member and said plate and being effective to hold said lever in different positions relative to said plate. 50

4. The combination of a sheet metal plate provided with an attaching element at one end and with a slot extending from a point adjacent to said attaching element to a point 55 adjacent to the opposite end, a link provided with oppositely extending studs at one end, a lever pivotally connected to said opposite end of the plate and pivotally connected to said link, and a retractile spring 60 having one end secured to said lever and having its other end secured to one of said oppositely extending studs, the other of said studs extending through said slot and being slidable therealong. 65

5. The combination with a door or the like and the casing thereof, of a plate provided with an aperture at one end and with means at its other end to secure it to said casing and with a slot between and extending toward said ends, a lever having one end connected to the door, a pivot extending through said aperture and connecting the other end of said lever to said plate, a link pivotally connected with said lever 70 and provided with a stud which extends through said slot and is slidable therealong, and a retractile spring having one end connected with said lever and having its other end connected to said link. 75

In testimony whereof I have hereunto set my hand.

ALVIS JACKSON HATHCOX.
